1. G. I.

FIG. 2.

FIG. 3.

FIG. 1 is a fragmentary top plan view of a bed spring unit or similar article, showing our new design as for a king-sized bed wherein the rows of coils are arranged in a 2-7-4-7-2 row transverse sequence, the portion broken away and omitted for convenience in illustration to indicate indeterminate length being identical to the adjacent portions;

FIG. 2 is a fragmentary enlarged scale perspective view; and

FIG. 3 is a fragmentary enlarged top plan view thereof.

This application is a division of copending application Ser. No. D. 22,430, filed Apr. 2, 1970, now design patent 224,284 of July 18, 1972.

We claim:

The ornamental design for a bed spring unit or similar article, as shown and described.
